UNITED STATES PATENT OFFICE.

RANDOLPH CROMPTON, OF CHATHAM, MASSACHUSETTS.

SHUTTLE-POSITIONING MEANS.

1,143,105.

Specification of Letters Patent. Patented June 15, 1915.

Application filed April 14, 1915. Serial No. 21,411.

To all whom it may concern:

Be it known that I, RANDOLPH CROMPTON, a citizen of the United States, and a resident of Chatham, in the county of Barnstable and State of Massachusetts, have invented an Improvement in Shuttle-Positioning Means, of which the following description, in connection with the accompanying drawings, is a specification, like characters on the drawings representing like parts.

This invention relates to shuttle positioning means and more particularly to means whereby the shuttle is locked in position in its box to permit effective replenishment of its filling carrier.

In order that the principle of the invention may be readily understood, I have disclosed a single embodiment thereof in the accompanying drawing, wherein—

Figure 1 is a transverse section taken through the loom having my invention applied thereto, but omitting unnecessary parts; Fig. 2 is a plan view of shuttle locking means constituting the preferred embodiment of my invention; Fig. 3 is a side elevation of the structure shown in Fig. 2; Fig. 4 is a transverse section upon the line 4—4 of Fig. 3 and looking toward the right in said figure; and Fig. 5 is a detail in transverse section of a portion of one end of the shuttle.

Many attempts have heretofore been made to position the shuttle accurately for weft replenishment, but so far as I am aware without satisfactory results. The flash or movement of the shuttle into its box is so quick that it is impossible, in a loom operating at high speed, to knock or move a part, member or device out of the path of the shuttle and get it back again in time to catch the shuttle and hold it in its proper position. It is also impossible, in a loom operating at high speed, to allow the shuttle to box and to flash or rebound from the picker and then to push the shuttle back again into place in time to permit the automatic change of filling carriers. Devices embodying the above principles have been tried in the mills but without satisfactory results in a loom operating at a high speed, such as has been necessary under present day conditions.

One of the important objects of my invention is to provide shuttle positioning means so constructed and arranged that the shuttle does not knock or move anything out of

its path when entering the shuttle box. In the preferred embodiment of my invention, the shuttle positioning means coöperating with the shuttle is, during the boxing of the shuttle, always in its operative position to restrain the shuttle from rebounding and is moved out of such position to allow the shuttle to be picked. Preferably the means co-acting with the shuttle has a fixed relation with respect to the path of movement of the shuttle during the entire boxing action of the shuttle and preferably the shuttle is provided with means rigid therewith or held in fixed position and adapted to engage with said co-acting shuttle positioning means.

Within the broad scope and purpose of my invention, many changes may be made while carrying out the principle thereof. So far as I am aware, no one has ever heretofore positioned a shuttle by co-acting means having the above characteristics and others hereinafter set forth, and I desire to claim the same broadly.

Referring more particularly to the drawings, I have in Fig. 1 represented the right hand end frame of the loom at 1. Therein it is pivoted at 2, the usual lay swords 3 having a lay 4, and the cam shaft 5 provided with the customary weft cam whereby through the detecting movement of the weft fork and the weft hammer, the loom may be stopped in the event of weft fault or failure.

The shuttle box is indicated generally at 6 in Fig. 1 and the co-acting picker stick at 7. The shuttle box may be of any desired construction, but preferably is provided with a resilient binder 8 pivoted at 9. Preferably, however, though not necessarily, I omit the usual leather facing from the said binder. The shuttle is indicated at 10 and may be of any suitable construction. It is herein represented as having a weft carrier 11 held therein by suitable jaws 12, permitting ejection of the exhausted filling carrier during the replenishing action. An important object of my invention is to effect the exact positioning of the shuttle for weft replenishment.

I have herein represented the shuttle 10 as having a plate or member 13 fixed thereto in any suitable manner, as, for example, by screws 14. Said plate may be of any suitable material, as, for example, of hardened steel, but within the scope of my invention, the shuttle may be so integrally shaped or formed as to co-act with the shuttle posi-

tioning means. Preferably said plate 13 is provided with teeth 15, which are here shown as graduated in size from the end 16 nearest the adjacent tip of the shuttle. Preferably the teeth do not project beyond the wall or face of the shuttle.

I provide the shuttle box with suitable co-acting shuttle positioning means. I use this language in a broad sense, inasmuch as 10 the co-acting shuttle positioning means need not be primarily a part of the shuttle box, but may be so positioned as to co-act with the box or the other parts of the box in effecting the positioning of the shuttle. 15 Therefore, throughout the specification and in the claims, when I refer to the shuttle box as having shuttle positioning means, such language is used in a broad and generic sense.

20 At a suitable point upon the shuttle box or on the loom lay adjacent thereto, I provide a suitable pin, screw or pivotal member 17, whereon I mount for rocking movement a lever 18, the outer end whereof has 25 pivotally mounted thereon a pinion 19, which throughout the boxing of the shuttle is held in fixed position to intercept the path of movement of the shuttle and in such relation that the teeth 15 of the plate 13 30 upon the shuttle mesh with the teeth of said pinion. Co-axial with the pinion 19 is a ratchet 20 and engaging with the teeth thereof is a pawl 21 mounted at 22 upon the lever 18, the construction and relation being 35 such that as the shuttle enters its box, the teeth 15 of the plate 13 engage the teeth of the pinion 19 and effect a rolling relation or engagement of said plate and pinion until the tip 23 of the shuttle strikes the 40 picker 7. Rebound of the shuttle, owing to its engagement with the picker is, however, prevented by the ratchet and pawl 20, 21, and therefore the shuttle is accurately held 45 in proper position for replenishment. I provide any suitable means co-acting with the lever 18 to hold the same in its fixed position during the boxing of the shuttle. For that purpose, I have represented a plate 50 spring 24 mounted upon the shuttle box and bearing against the lever 18. The strength of said spring is such as to hold said lever 18 with its pinion 19 in fixed and essentially rigid relation with respect to the shuttle and its plate 13. In order to permit the ensuing 55 pick of the shuttle, I provide means to disengage the pinion 19 from the teeth 15 of the shuttle just prior to such ensuing pick of the shuttle. While for this purpose, I may provide any suitable means, I have 60 herein represented the cam shaft 5 as having fixed thereon a cam 25, which is so shaped and positioned as to act just prior to the action of the cam, or means whereby the picker 7 is actuated to pick the shuttle from 65 said box 6. Pivoted at a suitable point 26

upon the frame of the loom, I have represented a lever 27 having a part 28 bearing upon the cam 25, which during each rotation acts to impart a lifting movement to said lever. A suitable spring 29 is provided 70 to return said lever to normal position and to hold it constantly in engagement with said cam 25. In order to prevent the movement of the lay 3 from interfering with the described movement of the lever 27, I preferably provide a sliding or movable connection between said parts. For that purpose, I have herein represented the lay and lay sword 3, 4 as having upper and lower guides 30, 31, within which is mounted for sliding 80 movement a suitable vertical rod 32 having attached thereto a block 33, the said block and the lever 27 being connected by a link 34 suitably pivoted to each of said parts. The lever 27 and the rod 32 constitute one 85 form of means for effecting disengagement of the pinion 29 from the rack or plate 13. For that purpose, I have represented the upper end of said rod 32 as forked at 35 and receiving within said forked portion the 90 arm 36 of a bell crank lever pivoted at 37 and having an arm 38 adapted to engage a suitably shaped end 39 of the lever 18. The construction and relation of the parts are such that after the boxing of the shuttle and 95 prior to the next ensuing picker thereof, the rod 32 is lifted and the lever 36, 38 is rocked upon its pivot 37 so as to press the inner or longer arm outwardly the opposite arm of said lever, carrying therewith the 100 pinion 19, the teeth of which are thereby disengaged from the teeth 15, thus freeing the shuttle for its next pick.

In order to insure the meshing of the teeth of the pinion 19 with the teeth 15 of the 105 plate or rack 13, I graduate the size of the teeth of the latter or vary them in suitable manner, as I have found upon experimenting that by providing teeth of such form, the liability of non-meshing engagement of 110 said teeth is avoided.

If desired, I may provide means whereby the entire mechanism may be held out of action until the weft carrier, assuming the weft remains unbroken, is nearly exhausted, 115 inasmuch as it is unnecessary to position the shuttle with absolute accuracy, if weft replenishment is not to occur. Such holding-out means need not, however, be employed.

From the foregoing description, it will be 120 apparent that I have provided means held or fixed in intercepting relation with the path of the shuttle, whereby the latter is accurately held or positioned for replenishment.

While I have described my invention as particularly applicable for weft replenishment, it is apparent that I am in no wise limited to such use of my invention.

Having thus described one illustrative 130

embodiment of my invention, I desire it to be understood that although specific terms are employed, they are used in a generic and descriptive sense and not for purposes of limitation, the scope of the invention being set forth in the following claims.

Claims:

1. In a loom, a lay, a shuttle box therefor, a shuttle having a series of holding projections, co-acting holding means held in position to engage said holding means in the entering or boxing movement of the shuttle, and being constructed and arranged to permit said holding projections to pass freely in one direction only, and means to permit picking of the shuttle from said box.

2. In a loom, a lay, a shuttle box therefor, a shuttle, said shuttle box and shuttle having shuttle positioning means in constant alining relation with each other in the path 20 of the shuttle throughout the boxing action of the shuttle in said box and means to hold said positioning means upon the shuttle box in position to prevent displacement of the shuttle 25 upon boxing.

3. In a loom, a lay, a shuttle box therefor and a shuttle, said shuttle box and shuttle being provided with shuttle positioning means having a rolling interengagement 30 with each other and means to hold said positioning means upon the shuttle box in position to prevent displacement of the shuttle upon boxing.

4. In a loom, a lay, a shuttle box therefor and a shuttle, said shuttle box and shuttle being provided with shuttle positioning means having a rolling relation with each other and means to hold said positioning 35 means upon the shuttle box in position to prevent displacement of the shuttle upon boxing.

5. In a loom, a lay, a shuttle box therefor and a shuttle, said shuttle box and shuttle being provided with shuttle positioning 40 means having a toothed engagement with each other.

6. In a loom, a lay, a shuttle box therefor and a shuttle, said box and shuttle having rack and pinion shuttle positioning means.

50 7. In a loom, a lay, a shuttle box therefor and a shuttle, said box and shuttle having rack and pinion shuttle positioning means, and means to disengage said rack and pinion means for the ensuing pick of the shuttle.

55 8. In a loom, a lay, a shuttle box therefor and a shuttle, said box and shuttle having rack and pinion shuttle positioning means, and means to disengage said rack and pinion means just prior to the ensuing pick of the shuttle.

60 9. In a loom, a lay, a shuttle box therefor and a shuttle, said box and shuttle having rack and pinion shuttle positioning means, and a ratchet, whereby movement of said pinion in one direction only is permitted.

10. In a loom, a lay, a shuttle box therefor and a shuttle, said box and shuttle having rack and pinion shuttle positioning means, and a ratchet, whereby movement of said pinion in one direction only is permitted, 70 and means to effect disengagement of said rack and pinion for the ensuing pick of the shuttle.

11. In a loom, a lay, a shuttle box therefor and a shuttle, said box and shuttle having co-acting holding means in engaging position during the boxing of the shuttle, means to maintain said holding means upon the shuttle box in position to prevent displacement of the shuttle upon boxing, and 80 co-acting means to prevent rebound of the shuttle upon boxing.

12. In a loom, a lay, a shuttle box therefor and a shuttle, said box and shuttle having co-acting holding means in engaging 85 position during the boxing of the shuttle, means to maintain said holding means upon the shuttle box in position to prevent displacement of the shuttle upon boxing, co-acting means to prevent rebound of the shuttle 90 upon boxing, and means to remove said holding means from holding position to permit picking of the shuttle.

13. In a loom, a lay, a shuttle box therefor, a shuttle, shuttle engaging, positioning 95 means having a substantially fixed bodily position during the entire boxing movement of the shuttle, in the path of movement of the shuttle, means to maintain said positioning means in such position during such 100 boxing action, and co-acting means to prevent rebound of the shuttle upon boxing.

14. In a loom, a lay, a shuttle box therefor, a shuttle having projections extending from the face thereof, shuttle positioning means 105 having a substantially fixed bodily position during the boxing movement of the shuttle, in the path of movement of the shuttle, and means to maintain said positioning means in such position during such boxing action. 110

15. In a loom, a lay, a shuttle box therefor, a shuttle, said shuttle and shuttle box having co-acting, toothed member at least one of which has teeth of varying size.

16. In a loom, a lay, a shuttle box therefor, a shuttle, said shuttle and shuttle box having co-acting, toothed members, at least one of which has graduated teeth.

17. In a loom, a lay, a shuttle box therefor and a shuttle having a toothed portion, the teeth whereof are of varying size, and co-acting shuttle positioning means to engage 120 said teeth.

18. In a loom, a lay, a shuttle box therefor, a shuttle, said shuttle having a toothed portion, the teeth whereof are graduated in size, and shuttle positioning means to engage 125 said teeth.

19. In a loom, a lay, a shuttle box therefor, a shuttle, fixed means upon the shuttle, and 130

engaging shuttle positioning means having a substantially fixed bodily position during the entire boxing movement of the shuttle, in the path of the movement of the shuttle, and means to maintain said positioning means in such position during such boxing action.

In testimony whereof, I have signed my name to this specification, in the presence of two subscribing witnesses.

RANDOLPH CROMPTON.
